CLAIM

The ornamental design for a charging case for a hearing aid, as shown and described.

DESCRIPTION

FIG. 1 is a top, front, right side perspective view of a charging case for hearing aid, showing my new design, closed, in a first configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, right side perspective view of a charging case for hearing aid of FIG. 1, shown open in a second configuration;

FIG. 9 is a top plan view thereof; and,

FIG. 10 is top, front, right side perspective view of a charging case for hearing aid of FIG. 1, shown open in a second configuration, in condition of use.

The broken lines depict portions of the charging case for hearing aid that form no part of the claimed design.
